UNITED STATES PATENT OFFICE.

FREEMAN MORSE, OF HASTINGS, NEW YORK.

IMPROVEMENT IN WATER-WHEELS.

Specification forming part of Letters Patent No. 40,704, dated November 24, 1863.

To all whom it may concern:

Be it known that I, FREEMAN MORSE, of Hastings, in the county of Oswego and State of New York, have invented a new and Improved Water-Wheel; and I do hereby declare that the following is a full, clear, and exact description of the same, reference being had to the accompanying drawings, making a part of this specification, in which—

Figure 1 is an elevation of my improved wheel, showing the casing or penstock partly in section. Fig. 2 is a plan of the same. Fig. 3 is a horizontal section of the wheel and penstock, the section being taken in the line *xx* of Fig. 1.

Similar letters of reference indicate corresponding parts in the several views.

The nature of my invention consists in having the buckets of the wheel extend in spiral form from the top to the bottom of the penstock in which it is fitted to run, and having the floor of the penstock level with the bottom of the water-way, so that the water shall strike square against the buckets and expend a portion of its force upon the wheel before it commences to rise in the penstock, whereby a much greater percentage of power is obtained from the same volume and fall of water than when the water has to ascend an inclined plane before it impinges the buckets of the wheel, as is usually the case in wheels of this character.

To enable others skilled in the art to which my invention appertains to fully understand the same, I will proceed to describe its construction and operation.

A represents a box or penstock for the wheel, with an inlet, *B*, the shape of which and the penstock is clearly represented in Fig. 3 of the drawings. The wheel is made of a log of wood, which is first turned in a lathe or otherwise to the proper size, and then the buckets formed on it by cutting spiral channels in its periphery of such shape as to leave ridges which on one and the same side are alike and of radial form. These ridges constitute the buckets of the wheel and their radial surfaces the faces of the buckets, the backs of which are of rounded form and extend from the bottom of one bucket to the top of the one next preceding it. In wheels of large size I propose to back the buckets with iron in the form of

metal plates, as shown in the accompanying drawings. These plates, after being fitted to the backs of the buckets, are secured by screws passing through into the wood. The buckets, at their upper ends, are inclosed by a rim, which is iron bound and rests on the top of the penstocks. This rim prevents the water passing through the penstock from escaping until it has passed some distance above it. The front and back side of the buckets, at their upper ends, are made parallel and more curved than lower down, for the purpose of giving a horizontal direction to the water and a less obstructed discharge.

The operation of my improved water-wheel is as follows: The water passes from the flume through the inlet *B* into the penstock *A*, where it comes in contact with the bucket *a* at its lower end, and a portion gradually ascends the same, while another portion passes on and meets the bucket *b*, and still another portion passes on and strikes the bucket *c*, each portion of water gradually ascending the bucket and expending the force of its momentum and that imparted to it by the gravity of the descending column. The water passing to the wheel continues to act upon each of the buckets until it has passed above the rim, whence, being no longer confined, it flows away with perfect freedom and without any disadvantageous reaction.

Having thus described my invention, what I claim as new, and desire to secure by Letters Patent, is—

A water-wheel having buckets formed upon it in the manner described, and extending from the top to the bottom of the penstock, in which it is fitted to run, in combination with the penstock when the floor of the same is level with the bottom of the inlet and water way, so that the water shall strike the buckets of the wheel and expend a portion of its force before commencing to rise in the penstock, as and for the purpose specified.

The above specification of my improvement in water-wheels signed this 29th day of July, 1863.

FREEMAN MORSE.
